W. H. FAIRCHILD

PLASTER BASE

Filed June 30, 1922

Inventor:
Walter H. Fairchild
By Fred Gerlach Atty

UNITED STATES PATENT OFFICE.

WALTER H. FAIRCHILD, OF CHICAGO, ILLINOIS, ASSIGNOR TO MID-WEST BOX COMPANY, OF ANDERSON, INDIANA, A CORPORATION OF INDIANA.

PLASTER BASE.

Application filed June 30, 1922. Serial No. 571,951.

The invention relates to plaster base and its object is to provide an improved base which comprises a suitable sheeting and a reinforcement or lath on the face thereof to 5 retain the plaster or stucco.

Another object of the present invention is to provide plaster base in sheet-form and in which provision is made for continuity in the reinforcing effect of the lath or reinforcement. Other objects will be apparent 10 from the description.

The invention consists in the several novel features hereinafter set forth and more particularly defined by the claims at the conclusion hereof.

In the drawing: Fig. 1 is a perspective of a structure embodying the invention, parts being shown in section. Fig. 2 is a horizontal section taken on line 2—2 of Fig. 1. Fig. 20 3 is a vertical section taken on line 3—3 of Fig. 1. Fig. 4 is a perspective of a complete sheet of the plaster-base.

The invention is exemplified in a plaster-base comprising a backing sheet and a sheet 25 of woven wire lath or fabric consisting of longitudinal strips of wire 11 connected by strips of wire 12 woven obliquely back and forth between and wrapped around strips 11 to form a suitable lath which is adapted 30 to retain plaster and to serve as a reinforcement for the wall when embedded in the plaster. The backing preferably comprises a back-liner or facing 7, a liner 8, an intermediate corrugated sheet 9, and a corrugated 35 sheet 10 secured to the front face of the liner 8. These liners and corrugated sheets are all formed of paper permanently secured together to form a stiff double-faced corrugated board with a corrugated plaster-face 40 which is waterproofed by immersing it in a suitable solution of asphaltum after or before the liners and corrugated sheets have been united by a suitable adhesive.

The woven-wire fabric extends over the 45 face of the backing formed by the corrugated sheet 10. The lath and backing are secured together before the base is applied to a building by staples 16 which extend through the backing and around the meshes of the 50 fabric to secure the backing and fabric together for convenience in handling the base. The wire fabric is cut into sheets of sufficient area to cover the front face of a sheet of backing, to extend beyond one of its longitudinal margins as at 17, and to project

slightly beyond its side-margins, as at 18. The other longitudinal margin is substantially conterminous with the other longitudinal margin of the sheet. The sheets of the base are secured by staples 20 to studs or 60 other suitable supports with their edges abutting to form a complete covering for the wall.

As a result of providing each sheet of base with woven fabric, which extends beyond 65 one longitudinal margin, the upper margin of the fabric on one sheet will overlap the lower margin of a vertically contiguous sheet when the sheets are secured to studs or suitable supports to form a wall so that the sheets 70 of fabric will collectively form a vertically continuous or uninterrupted reinforcement for the plaster or stucco. As a result of the projecting portions 18 at the side-margins of each sheet, the side margins will overlap at 75 the joints between laterally contiguous sheets when they are secured in position on studs or other suitable supports in the building of a wall and form horizontally continuous reinforcement for the plaster or stucco. By 80 providing sheets of the plaster base with these projecting marginal portions of lath or fabric, they will constitute a continuous reinforcement for plaster or stucco throughout the area of a wall which will effectively 85 prevent cracking of the plaster or stucco at the joints between the sheets.

The invention exemplifies a plaster-base in sheet-form which is composed of a backing-sheet and lath or fabric which will provide 90 continuous reinforcement for the plaster or stucco applied to the backing; also one in which corrugated board is used as a backing 95 with reinforcement which becomes continuous in a wall and prevents disruption of the plaster and distortion of the backing.

The invention is not to be understood as restricted to the details set forth, since these may be modified within the scope of the appended claims, without departing from the 100 spirit and scope of the invention.

Having thus described the invention, what I claim as new and desire to secure by Letters Patent, is:

1. A plaster base composed of a waterproof substantially stiff and rectangular backing sheet, and a metallic lath consisting of a series of wires extending in one direction and a second series of wires interwoven with the first series and extending angularly 105 110

with respect thereto, said lath being secured to and extending over the outer face of the sheet, the horizontal edges of said sheet being sufficiently wide to form seats against which the edges of similar bases are adapted to abut, the lath being extended so that wires of both series project beyond one of said horizontal edges to lap the abutting margin of one of the contiguous bases so as to form a continuous wall structure.

2. A plaster base composed of a waterproof substantially stiff and rectangular backing sheet, and a metallic lath consisting of a series of wires extending in one direction and a second series of wires interwoven with the first series and extending angularly with respect thereto, said lath being secured to and extending over the outer face of the sheet, the vertical edges of said sheet being sufficiently wide to form seats against which the edges of similar bases are adapted to abut, the lath being extended so that wires of both series project beyond one of its vertical edges to lap the abutting margin of one of the contiguous bases so as to form a continuous wall structure.

3. A plaster base composed of a waterproof substantially stiff and rectangular backing sheet, and a metallic lath consisting of a series of wires extending in one direction and

a second series of wires interwoven with the first series and extending angularly with respect thereto, said lath being secured to and extending over the outer face of the sheet, the vertical edges of said sheet being sufficiently wide to form seats against which the edges of similar bases are adapted to abut, the lath being extended so that wires of both series project beyond both of said vertical edges to lap the margins of the lath and sheet of the contiguous bases so as to form a continuous wall structure.

4. A plaster base composed of a waterproof substantially stiff and rectangular backing sheet, and a metallic lath consisting of wires extending horizontally and wires extending obliquely back and forth between said horizontal wires, said lath being secured to and extending over the outer face of the sheet, the vertical edges of the latter being sufficiently wide to form seats against which the edges of similar bases are adapted to abut, the oblique and horizontal wires of the lath being extended beyond both of said vertical edges to lap the margins of the lath and sheet on the contiguous bases so as to form a continuous wall structure.

Signed at Chicago, Illinois this 13th day of June, 1922.

WALTER H. FAIRCHILD.
